M. H. BENSON.
POWER TRANSMITTING MEANS.
APPLICATION FILED AUG. 23, 1920.

1,379,846.

Patented May 31, 1921.

UNITED STATES PATENT OFFICE.

MADISON H. BENSON, OF AUSTIN, TEXAS.

POWER-TRANSMITTING MEANS.

1,379,846.

Specification of Letters Patent. Patented May 31, 1921.

Application filed August 23, 1920. Serial No. 405,480.

To all whom it may concern:

Be it known that I, MADISON H. BENSON, a citizen of the United States residing at Austin, in the county of Travis and State 5 of Texas, have invented certain new and useful Improvements in Power-Transmitting Means, of which the following is a specification, reference being had to the accompanying drawings.

10 This invention relates to certain improvements in power transmitting means, and it is an object of the invention to provide a novel and improved device of this general character which serves to convert rotary 15 movement into reciprocatory movement and in such a manner whereby the reciprocating member makes one complete stroke or cycle while the rotating element makes two revolutions, thereby providing a two to one reduction without the use of gears or bolts.

20 The invention consists in the details of construction and in the combination and arrangement of the several parts of my improved power transmitting means whereby 25 certain important advantages are attained and the device rendered simpler, less expensive and otherwise more convenient and advantageous for use, as will be herein-after more fully set forth.

30 The novel features of my invention will hereinafter be definitely claimed.

In order that my invention may be the better understood, I will now proceed to describe the same with reference to the accompanying 35 drawings, wherein:

Figure 1 is a fragmentary view in elevation illustrating a power transmitting means constructed in accordance with an embodiment of my invention.

40 Fig. 2 is a fragmentary view partly in side elevation and partly in section of the structure illustrated in Fig. 1.

45 Fig. 3 is an enlarged fragmentary view partly in front elevation and partly in section illustrating certain of the parts in a second position, and

50 Fig. 4 is an enlarged fragmentary view partly in elevation and partly in section illustrating in detail the coaction between the guide shoe and ribs.

As disclosed in the accompanying drawings, H denotes a head of the type generally employed in connection with windmills and is provided with vertically spaced 55 bearings 1 for the reciprocating rod or plunger rod connector 2.

The head H is also provided with a journal or bearing 3 for a shaft 4, said shaft being adapted to be rotated by any mechanical means. The shaft 4 extends inwardly 60 of the head H and the inner end portion thereof is engaged with the axial center of a vertically disposed disk or wheel 5.

Produced on the outer face of the disk or wheel 5 is a cam groove or track C having a portion *a* thereof at one side of the axial center of the disk or wheel 5 substantially semi-oval with the axial center of the disk or wheel 5 to one side of the center of the major diameter of said semi-oval 70 portion *a*. The portion *a* of the groove or track C is continued by the portions *b* of the same radii but each of a radius less than the radius of the adjacent parts of the portion *a*.

75 The central part of the portion *b* of the cam groove or track C has its outer side wall inwardly disposed, as at *c*, so that said outer wall will be substantially in continuity with the outer wall of the supplemental cam groove or track C'. This supplemental cam groove or track C' is arranged within the field defined by the cam groove or track C and has a portion *d* substantially semi-oval and said portion *d* is continued by the portion *e* of a greater radius than the adjacent parts of the portion *d*.

80 The lower portion of the side walls of the cam grooves or tracks C and C' at their junction are defined by the inwardly disposed ribs 6 extending a desired distance 90 inwardly of the junction and the outer wall of the cam groove or track C at opposite sides of the point *c* is also provided in its lower part with the inwardly disposed ribs 6'.

95 The rod or connector 2 is provided with a pin 7 extending in a direction toward the disk or wheel 5 and mounted upon the pin 7 is a roller 8 which is adapted to ride within the outer portions of the cam grooves or tracks C and C'. Engaged with the pin 7 inwardly of the roller 8 is an elongated shoe 9 elliptical in form of a major diameter substantially equal to the space between 100 opposed ribs 6. The shoe 9 is also of a length in excess of the width of either of the cam grooves or tracks C and C' and particularly at their junction.

105 As the disk or wheel 5 rotates in one direction, as indicated by the arrow in Fig. 1, the rod or connector 2 moves upwardly

during one and one-half revolutions of the disk or wheel 5 and downwardly upon a one-half revolution, so that two revolutions of the disk or wheel 5 are required in order 5 to permit the rod or connector 2 to make one complete stroke. The requisite travel of the wheels 8 within the cam grooves or tracks C and C' is assured by the shoe 9.

From the foregoing description it is 10 thought to be obvious that a power transmitting means constructed in accordance with my invention is particularly well adapted for use by reason of the convenience and facility with which it may be assembled and operated, and it will also be obvious 15 that my invention is susceptible of some change and modification without departing from the principles and spirit thereof and for this reason I do not wish to be 20 understood as limiting myself to the precise arrangement and formation of the several parts herein shown in carrying out my invention in practice except as hereinafter claimed.

25 I claim:

1. A device of the character described comprising a member supported for reciprocatory movement, a rotary member, said rotary member being provided with a main 30 cam track, a supplementary cam track ar-

ranged within the field defined by the main cam track, said tracks being in communication one with the other, a part carried by the reciprocating member and traveling within the cam tracks, and a guide 35 shoe carried by the reciprocating member and traveling in the cam tracks, the lower portions of the side walls of the cam tracks at their junction being provided with inwardly disposed ribs, the guide shoe trav- 40 eling between said ribs.

2. A device of the character described comprising a member supported for reciprocatory movement, a rotary member, said rotary member being provided with a main 45 cam track, a supplementary cam track arranged within the field defined by the main cam track, said tracks being in communication one with the other, a part carried by the reciprocating member and traveling 50 within the cam tracks, and a guide shoe carried by the reciprocating member and traveling in the cam tracks, the side walls of the cam tracks at their junction being provided with inwardly disposed ribs, the guide 55 shoe traveling between said ribs.

In testimony whereof I hereunto affix my signature.

MADISON H. BENSON.
